UNITED STATES PATENT OFFICE.

WILLIAM MILLER SAUNDERS, OF WATERBURY, CONNECTICUT, ASSIGNOR TO THE HOGE MANUFACTURING COMPANY, OF NEW YORK, N. Y., A CORPORATION OF NEW YORK.

PROPEL PENCIL.

Application filed July 21, 1921. Serial No. 486,502.

To all whom it may concern:

Be it known that I, WILLIAM M. SAUNDERS, a citizen of the United States, residing at Waterbury, Connecticut, have invented certain new and useful Improvements in Propel Pencils, of which the following is a full, clear, and exact description.

My invention relates to propel pencils and has for its object to provide an improved pencil which is economical to manufacture and efficient in operation. It further has for its object to provide a simply constructed pencil which will not be injured by continuing to turn the propel mechanism when the follower has reached either limit of its throw.

The following is a description of an embodiment of my invention, reference being had to the accompanying drawings, in which,

Fig. 1 shows a pencil embodying my invention, with the outer casing thereof shown in longitudinal section;

Fig. 2 shows a longitudinal section of the pencil as a whole taken on the line 2—2, Fig. 1;

Fig. 3 shows a section on the line 3—3, Fig. 2; and

Fig. 4 shows a section on the line 4—4, Fig. 2.

Referring more particularly to the drawings, 1 is a casing having a tapered point portion 2. Within this casing is a tubular follower-carrier 3 rigidly secured to a support or knob 4 which extends from within the casing to the outside thereof, its outer end being provided with a knurled portion 5 to which a ring 6 may be connected as shown. The support is provided with an annular recess into which the upper end of the casing is spun as shown at 7 so as to hold the support in place without interfering with its movement of rotation. The support and follower-carrier are thus held in position.

The lower end of the follower-carrier is slightly reduced and is slotted as shown at 8, the jaws thus formed being sufficiently contracted to hug the lead 9 and in such relation to the internal surface of the tapered portion 2 at a point near the extreme lower end thereof as to be in close contact therewith when the lead 9 is inserted. These relations enable the lead to be inserted through the point and result in holding the lead 9 firmly against lateral movement, the

lead being prevented from falling out by the gripping action of the jaws. The internal bore of the carrier above the jaws is slightly enlarged as shown at 10. The carrier is provided with a slot 11 through which the bent end 12 of the follower 13 protrudes. The carrier is surrounded by a spring 14 whose lower end makes a binding engagement with the internal surface of the tapered portion 2 and whose upper end bears against a bushing 15 which enters the upper portion of the spring and is provided with a flange 16 against which the upper end of the spring bears. The spring is so proportioned that it is held by the support 4 and bushing 15 under slight compression so as to maintain the binding engagement with said inner surface of the tapered portion 2 under normal conditions. The spring 14 is slightly removed from the internal surface of the body portion of the casing so as not to make binding contact therewith, with the result that when the follower reaches its lowermost limit of movement and thereafter acts to withdraw the lower end of the spring from binding engagement with the inner surface of the tapered portion 2, the spring is free to revolve if the follower-carrier is thereafter revolved in the same direction. When the support 4 is revolved in the opposite direction, the follower permits the spring to seat, and therefore by reason of its engagement with the spring 14, is retracted. When the follower reaches its uppermost position it causes the spring 14 to be compressed until the end 12 of the follower, as the carrier is further turned, snaps by the upper end of the spring. The mechanism, therefore, can not be injured by turning the support 4 together with the follower-carrier continuously to any amount in either direction.

The flange 16 provides a bearing surface engaging the lower face of the support 4 and is revolvable relatively to said support and also relatively to the casing 1, so that when the lower end of the spring is withdrawn from its binding engagement the upper end, together with the bushing 15, can be revolved with the support 4 relatively to the casing 1, and when the follower is being moved downward to propel the lead, the upper end of the spring is kept from engagement with the lower face of the support 4 so as not to interfere with its movement. The limits of movement of the follower are defined by the

lower end of the slot 11 and the lower end of the bushing 15.

As will be evident to those skilled in the art, my invention permits of various modifications without departing from the spirit thereof or the scope of the appended claims.

What I claim is:

1. In a propel pencil, a casing having a tapered point, a slotted tubular carrier extending through the body of said casing and terminating in close relation to the inner surface of said tapered point, a revolvable support for said carrier rigidly secured thereto and extending from within said casing to the outside thereof, said support having an external lateral annular recess into which the extreme end of said casing projects, a follower within said carrier having a portion extending through the slot therein and a spiral spring within said casing with which said follower portion engages, said spring being of smaller external diameter than the internal diameter of said casing and held by said support so that its lower end is in binding engagement with the internal surface of said tapered point.

2. In a propel pencil, a casing having a tapered point, a slotted tubular carrier extending through the body of said casing and terminating in close relation to the inner surface of said tapered point, a revolvable support for said carrier rigidly secured thereto and extending from within said casing to the outside thereof, said support having an external lateral annular recess into which the extreme upper end of said casing projects, a follower within said carrier having a portion extending through the slot therein, a spiral spring within said casing with which said follower portion engages, said spring being of smaller external diameter than the internal diameter of said casing and held by said support so that its lower end is in binding engagement with the internal surface of said tapered point, and a flanged bushing within the upper end of said spring bearing against said support, said support being revolvable relatively thereto and to said casing, said spring being compressible by said follower when at the

end of its downward movement so as to be withdrawn from binding engagement with said internal surface of said point, and revolvable relatively to said casing when so compressed.

3. In a propel pencil, a casing having a tapered point, a slotted tubular carrier extending through the body of said casing and terminating in close relation to the inner surface of said tapered point, a revolvable support for said carrier rigidly secured thereto and extending from within said casing to the outside thereof, said support having an external lateral annular recess into which the extreme upper end of said casing projects, a follower within said carrier having a portion extending through the slot therein, a spiral spring within said casing with which said follower portion engages, said spring being of smaller external diameter than the internal diameter of said casing and held by said support so that its lower end is in binding engagement with the internal surface of said tapered point, said spring being compressible by the engagement of said follower with the upper portion thereof so that said follower can be turned by the upper end of said spring, and a flanged bushing in the upper end of said spring surrounding said carrier and bearing against the inner end of said support, said support being revolvable relatively to said casing.

4. A propel pencil having in combination a casing composed of a shell tapered at one end, a knob revolvably secured in the upper end of said casing, a slotted follower-carrier secured to said knob, a follower within said carrier and having a portion projecting through the slot therein, and a spring within said casing and surrounding said carrier so as to be engaged by the projecting portion of the follower, said spring having its body portions of smaller external diameter than the bore of the adjacent portions of the body of said casing, and having an end portion in direct binding engagement with said casing shell.

WILLIAM MILLER SAUNDERS.
